UNITED STATES PATENT OFFICE.

WEBB JAY, OF CHICAGO, ILLINOIS.

VACUUM FUEL-FEED SYSTEM.

1,279,115.

Specification of Letters Patent. Patented Sept. 17, 1918.

Application filed January 2, 1918. Serial No. 209,873.

To all whom it may concern:

- Be it known that I, WEBB JAY, a citizen of the United States, residing at Chicago, in the county of Cook and State of Illinois, 5 have invented certain new and useful Improvements in Vacuum Fuel-Feed Systems, of which the following is a specification, reference being had to the accompanying drawings, forming a part thereof.
- 10 The purpose of this invention is to provide in a vacuum fuel feed system new and improved means for obviating the danger of overflow or discharge of liquid fuel or vapor thereof, from the reserve chamber in 15 case of over-heating of the apparatus. It consists in the elements and features of construction shown and described, as indicated in the claims.

In the drawings:—

- 20 Figure 1 is a side elevation, somewhat diagrammatic, showing a familiar type of vacuum fuel feed system installed upon the engine of an automobile.

- 25 Fig. 2 shows the several parts of such system partially in vertical section, and diagrammatically as to their relative positions.

- 30 In the drawings, 1 is the main low level fuel supply tank from which a tube, 2, leads to the vacuum chamber or receiving chamber, 3, of the vacuum fuel feed device, of which 35 4 is the reserve fuel chamber or reservoir which is supplied from the vacuum chamber by the flow of the liquid past the check valve, 5. 6 is a suction pipe leading from the vacuum chamber, 3, to a source of suction, as the pipe 7, leading to the intake manifold of the engine. 8 is an air vent pipe leading from the upper part of the fuel 40 45 reserve chamber or reservoir, 4, back to the main low level fuel supply tank 1, which said pipe enters so as to be open in the upper part thereof above the intended level of the fuel supply therein. It will be understood that the main low level fuel supply tank, 1, has an air vent, shown at 1^a, so that atmospheric pressure is at all times operative in the upper part of that tank, upon the liquid therein, as well as for access through the air 50 55 vent pipe, 8. It will be understood that the vacuum chamber, 3, has an atmosphere inlet as shown at 3^a, and that any familiar or

suitable means may be employed to alternate the dominance of suction operating through the suction pipe, 6, and atmospheric pressure 55 operating through the air inlet, 3^a. In the drawings there is shown conventionally the most familiar of the expedients for this purpose, comprising a snap action device, 10, with the valves, 11 and 12, which control respectively the suction and the atmospheric inlet operated by a float, 13, to change the dominance upon change of level of liquid in the vacuum chamber.

The operation of this device in supplying 65 the carburetor is that which is perfectly familiar. The feature which distinguishes the invention embodied in this structure, is that the atmospheric pressure for permitting discharge by gravity of the liquid fuel from 70 the fuel reserve chamber, 4, is transmitted through the pipe, 8, from the upper part of the main fuel supply tank, 1, so that in case of overheating of the device, causing expansion of the liquid fuel in the reserve 75 fuel chamber, 4, or in both that chamber and the vacuum chamber 3, under any circumstances, the pressure thus generated or the vapor thus produced would find relief through the air vent pipe 8, and any liquid 80 fuel which might be discharged by such pressure will be carried over into the fuel supply chamber, 1, and all danger of its discharge, either as vapor or liquid, in the vicinity of the engine where damage might 85 be done by its ignition is entirely avoided.

I claim:—

In a vacuum fuel feed system, in combination with a vacuum chamber, a main low level fuel tank; a conduit from the main 90 tank to the vacuum chamber, a reservoir or reserve fuel chamber into which the vacuum chamber discharges liquid; a valve controlling such discharge; means for alternating the dominance of suction and pressure on 95 the liquid contents of the vacuum chamber, and an air vent pipe leading from the reserve fuel chamber to the upper part of the main fuel tank.

In testimony whereof I have hereunto set 100 my hand at Chicago, Illinois, this 12th day of December, 1917.

WEBB JAY.
